CONTAINER TOP

Anthony Di Domenico, Forest Hills, Long Island,
and Dominick Di Domenico, Brooklyn, N. Y.

Application January 4, 1938, Serial No. 183,246

4 Claims. (Cl. 229—5.5)

The invention relates to the fabrication of boxes or containers made from materials of the nature of cardboard, pasteboard, or like fibrous stock, and especially to the fabrication of a top or cover member for such container. More particularly, the invention consists in providing a cover member having a side strip of paper board stock, covered with a thin sheet of decorative paper, constituting a ring adapted to be assembled with a single sheet of cardboard constituting the head of the cover member, the assembled top being designed to telescopically engage the open end of the container and to form therewith a completed box.

In its broadest aspect, the present invention consists in forming a bead throughout the upper peripheral edge of the ring constituting the side wall of the cover member, flattening such bead substantially completely so as to form a flange extending inwardly from such side wall member, applying a quantity of glue or other adhesive material to the lower surface of the flange and securing, by means of such adhesive, a single sheet of cardboard constituting the crown or head of the container top, to such side wall.

In the fabrication of a top or cover member for a container of this general type, it has been the practice to form a bead of substantially fully rounded form at the upper periphery of the ring constituting the side wall of the cover, and it was sought to prevent the tendency of such rounded bead to unroll by applying thereto a structure consisting of two sheets of cardboard, one formed with a peripheral groove into which the bead was adapted to fit snugly, and the other, or bottom member, formed of a single sheet of stock positioned immediately below the first or crown portion, and extending so as to have its peripheral edge abut the portion of the ring member immediately below the rounded bead, thereby maintaining the cover structure in frictional engagement with the inner and lower surfaces of the rounded bead.

We have found that such prior art construction does not, to any appreciable extent, prevent the loosening of the contact between the head of the cover member and its side wall. On the contrary, such a frictional contact, in spite of the snug fit by which it is produced, yields a structure which is not characterized by any particularly effective strengthening of the box structure.

By our novel construction of container top, we attain a sturdiness and added strength characterizing the joint between the elements of the container top, which is not dependent upon any frictional holding of the elements thereof together, but being dependent upon positive adhesive contact between such elements, secure a measure of added strength of the joint, and, therefore, an added sturdiness of the entire box structure with-

out resort to the use of a lining member in the cover structure, such as has been found necessary in the fabrication, in accordance with the prior art, of similar types of container tops.

In addition to the increased strength, rigidity, and therefore, sturdiness, of the container top structure, our novel construction is characterized by a pleasing appearance of the container, a feature of considerable importance in the fabrication of fancy boxes which, however, must be capable of being produced at relatively low cost and for competition with more expensively produced boxes.

Our novel structure, therefore, is attractive in appearance, sturdy in structural composition, and may be fabricated at a cost considerably lower than similar boxes of conventional construction.

A specific embodiment of our invention is illustrated in the accompanying drawing, in which Fig. 1 is a partial vertical section through a container having a top or cover member in the fabrication of which our novel structure has been embodied; Fig. 2 is a fragmentary vertical section through the ring member constituting the side wall of the container top, showing the formation of the rounded bead at the upper edge thereof; Fig. 3 is a view, in similar section, of such ring member after the bead at the upper edge thereof has been substantially completely flattened; and Fig. 4 is a vertical section through the container cover wall and crown, showing the assembled relation of such elements.

Referring more particularly to the drawing, in which similar reference characters identify similar parts in the several views, the body of the container is designated generally as 5, such body having the upper peripheral edge thereof formed with a rounded bead 6. Our invention is concerned not with the structure of the container body, but with that of the top or cover member, 40 which is constituted of a ring 7 of cardboard, pasteboard or like fibrous material formed, as shown in Fig. 2, with a substantially circular bead 8. This bead is then completely flattened so as to have the form of a flange 9 substantially as shown in Fig. 3, in which the two parts of the flange are in substantial contact at the core 10 of the flange.

As shown particularly in Figs. 2 to 4, the ring member may be provided with facing layers of paper 11, constituting finishing strips which may be suitably ornamented by decorative printing or otherwise.

The crown portion of the container top is constituted of a strip 12 of cardboard, pasteboard or the like, such strip having its peripheral edge portions bent downwardly and outwardly so as to form a recess throughout the peripheral edge of the crown portion, in which recess the flange 9 is adapted to be seated.

The assembling of our novel structure of container top, in contra-distinction to the practice of the prior art, is effected by applying a layer 13 of glue or other suitable adhesive material to the 5 bottom surface of the flange 9 and pressing the peripheral edge portion of the crown member 12 against such adhesive material so as to effect a joining, by such adhesive, of the peripheral edge portion of the crown 12 to the bottom of the 10 flange 9.

The crown member 12 of the cover may advantageously be provided with a surfacing strip 14 carrying the same design or embellishment as does the facing strip 11 of the side wall of the container 15 top, so as to maintain substantially the same design throughout the outer surface of the completed container cover.

It will be noted that in accordance with our novel construction, as shown clearly in Figs. 1 and 20 4, the portion of the crown member constituting the side wall forming the recess along its peripheral edge, is not anywhere in contact with the inner edge of the flange 9. By this construction, a particularly attractive appearance of the container 25 top, with a substantially open ridge 15 throughout its peripheral edge, is produced, such ridge breaking up the continuity of surface produced by the juncture of the crown and the side wall of the container top.

30 It will also be noted that the peripheral edge of the crown 12, in the assembly thereof with the side wall of the container top by means of the layer of adhesive 13, is somewhat removed from the inner face of the ring constituting the side wall immediately below the flange 9, there being a clear 35 space 16 between the peripheral edge of the crown 12 and the ring 7, so that no pressure is applied by such peripheral edge against the side wall. Thus, no stresses or strains are possibly produced by having an inordinate pressure applied by the peripheral edges of the crown member against the side wall, such as characterize the structures of the prior art and which we have found objectionable as producing a tendency of causing a loosening of 40 the joint between the crown member and side wall of the container top. By eliminating all frictional contact between the crown member and the side wall, we are enabled to produce a container top at low cost, and, not being dependent upon 45 merely frictional holding of the elements thereof together, the strength, sturdiness and, therefore, the life of the container is appreciably increased. This is an important feature in connection with boxes of the general type to which the invention relates, as such boxes are usually used 50 to contain commodities such as candy and powder, which are not removed in toto from the container, but are dispensed therefrom at periodical intervals during a period of time usually of considerable duration commensurate with the quantity 55 of the supply of commodity contained in the box.

While we have described a specific embodiment of our invention, it is obvious that various changes 60 therein, particularly in the arrangement and configuration of the several elements thereof, within the ambit of the claims, may be made without departing from our invention.

We claim:

70 1. A container top comprising a substantially rigid ring member constituting a side wall of the

container top, the upper edge thereof being turned inwardly toward the axis of the ring and then outwardly with the outermost portion positioned immediately below the inwardly turned portion, so as to constitute a substantially flattened flange at 5 the end of the ring, a crown member for said container top, the peripheral edge portions thereof being turned downwardly and outwardly so as to constitute a recess for receiving said flattened flange of the ring member, and a layer of adhesive 10 between the lower surface of said flange and the upper surface of the peripheral edge portion of the crown member constituting the bottom of said recess.

2. A container top comprising a substantially 15 rigid ring member constituting a side wall of the container top, the upper edge thereof being turned inwardly toward the axis of the ring and then outwardly with the outermost portion positioned immediately below the inwardly turned portion, so as to 20 constitute a substantially flattened flange at the end of the ring, a crown member for said container top, the peripheral edge portions thereof being turned downwardly and outwardly so as to constitute a recess for receiving said flattened 25 flange, and a layer of adhesive between the lower surface of said flange and the upper surface of the peripheral edge portion of the crown member constituting the bottom of said recess, the portion 30 of the crown member constituting the side wall of said recess being spaced from the inner edge of the flange.

3. A container top comprising a substantially rigid ring member constituting a side wall of the container top, the upper edge thereof being turned 35 inwardly toward the axis of the ring and then outwardly with the outermost portion positioned immediately below the inwardly turned portion, so as to constitute a substantially flattened flange at the end of the ring, a crown member for said container top, the peripheral edge portions thereof being turned downwardly and outwardly so as to 40 constitute a recess for receiving said flattened flange, and a layer of adhesive between the lower surface of said flange and the upper surface of the 45 peripheral edge portion of the crown member constituting the bottom of said recess, the peripheral edge of the crown member being spaced from the portion of the ring immediately below said flange.

4. A container top comprising a substantially rigid ring member constituting a side wall of the container top, the upper edge thereof being turned inwardly toward the axis of the ring and then outwardly with the outermost portion positioned immediately below the inwardly turned portion, so as to 50 constitute a substantially flattened flange at the end of the ring, a crown member for said container top, the peripheral edge portions thereof being turned downwardly and outwardly so as to 55 constitute a recess for receiving said flattened flange, and a layer of adhesive between the lower surface of said flange and the upper surface of the peripheral edge portion of the crown member constituting the bottom of said recess, the portion 60 of the crown member constituting the side wall of said recess being spaced from the inner edge of the flange and the peripheral edge of the crown member being spaced from the portion 65 of the ring immediately below said flange.
